UNITED STATES PATENT OFFICE.

CHRISTOPHER J. MEYER, OF MILWAUKEE, WISCONSIN, ASSIGNOR TO EVINRUDE MOTOR COMPANY, OF MILWAUKEE, WISCONSIN, A CORPORATION OF WISCONSIN.

DETACHABLE ROWBOAT-MOTOR.

1,231,046.

Specification of Letters Patent. Patented June 26, 1917.

Application filed March 1, 1915. Serial No. 11,414.

To all whom it may concern:

Be it known that I, CHRISTOPHER J. MEYER, a citizen of the United States, residing at Milwaukee, county of Milwaukee, 5 and State of Wisconsin, have invented new and useful Improvements in Detachable Rowboat-Motors, of which the following is a specification.

My invention relates to improvements in 10 that class of row boat motors, shown and described in Letters Patents of the United States, No. 1001260, dated August 22, 1911, and No. 1087162, dated October 12, 1912.

In the propelling mechanisms of the class 15 above referred to, it has heretofore been customary to mount the pump upon the casing, which incloses the submerged gearing and provides bearings for the shaft which carries the propeller wheel, but the propeller 20 wheels of this type are swung from side to side for steering purposes, and it is also desirable that they be reversible. In a companion application bearing even date herewith, I have shown and described reversing 25 mechanism, in which the lateral thrust of the propeller blades is utilized to automatically reverse the propeller, means being provided for automatically relieving the propeller supporting shaft from tiller control, 30 in order that the reversal may be thus automatically accomplished. But as each of these reversing movements takes place in the same direction of rotation about the axis of the supporting shaft, it is not possible to 35 locate the pump upon the casing of the propeller shaft, if a separate tube is employed to deliver the water from the pump to the water jacket of the internal combustion motor.

40 The object of my invention therefore is to provide means whereby the pump may be supported in a stationary position in a propelling mechanism of this class and such a pump operated from the propeller shaft regardless of the rotative adjustment of the 45 propeller and said shaft.

In the drawings—

Figure 1 is a side elevation of the lower portion of a propelling mechanism of the 50 general type above described with my invention embodied therein.

Fig. 2 is a detail view of the segment block and sleeve, which connects the propelling mechanism with a support adapted to be 55 detachably connected with the transom of a

row boat, as shown and described in said former patents.

Fig. 3 is a detail view of a clamping member adapted to engage the supporting shaft of the propeller and to form a bearing for 60 the segment block shown in Fig. 2.

Fig. 4 is a detail view of the pump and pump supporting clamping member detached.

Fig. 5 is a detail view showing the clamp- 65 ing member of Fig. 3 in place.

Like parts are identified by the same reference characters throughout the several views.

1 is a tubular supporting shaft to the 70 lower end of which a casing 2 is secured, which serves as a housing for the propeller shaft, the gearing connecting said shaft with a driving shaft extending downwardly through the tube 1, substantially as shown 75 in the prior patents above referred to. A pump actuating rod 3 is reciprocated from the propeller shaft substantially as shown and described in said former patents, but for the purpose of my present invention, this 80 rod 3 does not serve as a pump plunger but supports a ring 4, which loosely encircles the shaft 1 and forms an annular bearing for a pump plunger 5, which projects downwardly from the cylinder 6 of the pump carried by 85 a clamping bracket 7. The upper end of the cylinder 6 is provided with a nipple 8, having an outlet port and adapted to facilitate connecting the pump with the water jacket of an internal combustion motor. The motor 90 may be assumed to be of the same general type as that shown in said former patent, No. 1001260, and it is therefore not illustrated or described herein.

A supporting bracket 11, adapted to be 95 clamped to the transom of a boat, is provided with a set of segmental arms 12, which pass through slots 13 (Fig. 2) in a segment block 14. The arms 12 are clamped in any desired position of adjustment by set screws 100 16, the arms being preferably provided with sockets 17 in which said screws may engage.

The segment block 14 is provided with a depending sleeve 18, which is engaged by the clamping bracket 7, which supports the 105 pump. Said clamping bracket is provided with ears 20 through which the clamping bolt 21 may pass.

A clamping sleeve 25 embraces the propeller supporting shaft 1 above the block 110

14. This sleeve 25 is split near its lower end and is provided with outwardly projecting ears 26, through which a clamping bolt 27 may pass, whereby the sleeve may be bound 5 securely upon the shaft 1. The lower end of this sleeve affords a bearing against which the segment block 14 abuts, and the upper end of the sleeve is provided with a catch 28 adapted to be engaged by a tiller lever, 10 whereby the propeller supporting shaft 1 may be rotated to swing the propeller from side to side for steering purposes.

With the above described construction, it is obvious that the pump 6 will be supported 15 and held in a stationary position by the bracket 11, arms 12, segment block 14, sleeve 18 and clamping member 7. Also that the propeller supporting shaft 1 will be supported from the block 14 through the 20 clamping sleeve 25, which, however, is adapted to rotate upon the segment block 14, thereby permitting a rotary movement of the shaft 1. And in view of the fact that sleeve 25 is clamped to the shaft 1, it is obvious that 25 it may be adjusted lineally to allow the shaft 1 to be raised or lowered, thereby adjusting the propeller in proper relation to the boat with which it is connected. The annulus 4, upon which the pump plunger 5 30 bears, will of course rotate whenever shaft 1 and casing 2 are rotated. But as this annulus is concentric with the shaft 1, it will bear upon the pump plunger 5 in any position of rotative adjustment. Therefore an 35 upward movement of the reciprocating pump actuating rod 3 will be effective to operate the pump from any position of such rotative adjustment, and a downward movement of the rod 3 will permit a corresponding 40 downward movement of the plunger 5, either by gravity or under the tension of a spring within the pump cylinder. By providing the pump cylinder with the clamping member 7 instead of permanently securing 45 it to the sleeve 18, I secure the added advantage of being able to adjust the pump cylinder rotatively with reference to the sleeve 18 and thereby bring the pump outlet to the position most convenient for connection 50 with a pipe leading to the water jacket of the motor.

I claim—

1. A supporting member for propeller shafts, comprising a bracket engaging block having a downwardly projecting sleeve 55 through which a propeller supporting shaft may pass, and a pump cylinder provided with a clamping member engaging said sleeve.

2. The combination with a propeller supporting shaft, of a sleeve loose on said shaft, a bearing sleeve clamped to said shaft above said loose sleeve, and a pump cylinder clamped to said loose sleeve.

3. The combination with a propeller supporting shaft, of a sleeve loose on said shaft, a bearing sleeve clamped to said shaft above said loose sleeve, and a pump cylinder clamped to said loose sleeve, together with 70 a set of supporting arms connected with said loose sleeve and adapted to support the propeller shaft while permitting rotative adjustments thereof.

4. The combination with a supporting boat engaging bracket, of a sleeve connected therewith, a propeller supporting shaft extending loosely through said sleeve, a clamping member secured to said shaft above said sleeve and adapted to bear thereon to support the shaft from the sleeve and 80 bracket, a pump cylinder secured to the sleeve, and a pump operating rod supported from the propeller supporting shaft and provided with a ring encircling said shaft, said pump cylinder having a plunger arranged with one end bearing upon said ring, 85 substantially as described.

5. The combination with a stationary propeller supporting member, of a pump cylinder adjustably clamped thereto, a propeller supporting shaft extending through said stationary support and rotatively adjustable therein, and means carried by the propeller supporting shaft for operating the pump in any desired position of rotative adjustment. 95

In testimony whereof I affix my signature in the presence of two witnesses.

CHRISTOPHER J. MEYER.
